UNITED STATES PATENT OFFICE.

HARRY AGLOW, OF NEW YORK, N. Y., ASSIGNOR TO ARTCRAFT METAL STAMPING CORPORATION, A CORPORATION OF NEW YORK.

DESIGN FOR A BACKPLATE FOR LIGHTING FIXTURES.

Application filed February 15, 1924. Serial No. 8,642. Term of patent 3½ years.

To all whom it may concern:

Be it known that I, HARRY AGLOW, a subject of the King of Great Britain, and a resident of the city of New York, county of Bronx, and State of New York, have invented a new and original and ornamental Design for a Backplate for Lighting Fixtures, of which the following is a specification, reference being had to the accompanying drawing, forming a part hereof.

The drawing shows a front elevation of the backplate for lighting-fixtures.

I claim:

The ornamental design for a backplate for lighting-fixtures substantially as shown.

HARRY AGLOW.
